PLATE CLAMPING MECHANISM FOR
PRINTING MACHINES

William F. Huck, Richmond Hill, N. Y., assignor
to R. Hoe & Co., Inc., New York, N. Y., a corpora-
tion of New York

Application May 19, 1939, Serial No. 274,509

14 Claims. (Cl. 101—415.1)

This invention relates to clamps for securing printing plates to the form cylinders of printing machines, and more specifically to an arrangement including a plate clamping support, for holding the plate clamps in the cylinder at a plurality of positions, to accommodate plates having different dimensions.

The form of plate clamp and support shown herein is especially adapted to lithographic, intaglio and other machines of the class which print from relatively thin plates that are held on the cylinder under tension, by clamps engaging the leading and trailing edges of the plate.

In lithographic printing especially, it is sometimes necessary to use plates of different lengths, but this cannot be done on presses as heretofore constructed, and it therefore has been necessary for a printing plant to have a printing machine for each size of plate that it is desired to use.

In order to provide a printing machine that is adapted to receive more than one size of plate and thereby reduce the number of printing machines required in a printing establishment to handle a certain range of work, as hereinafter disclosed, there is now provided a plate cylinder and a plate clamping mechanism therefor, having certain of its members movable into different positions to thereby adapt them to this requirement.

An object of the invention is to provide in a plate cylinder, means including a removable plate clamp holding segment, and a plate clamping mechanism, whereby either of two lengths of plates may be accommodated.

Another object is to provide in a plate cylinder for a printing machine adapted to print from relatively thin plates a reversible segment part arranged to receive and hold a removable plate clamping mechanism which includes a plate clamping bar adjustably secured to the segment part and having plate clamping jaws adapted to engage a relatively thin plate.

It is also an object of this invention to provide a lithographic plate cylinder of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawing, wherein:

Figure 1 is a broken top plan view of an improved plate cylinder with the improved plate clamping means of this invention shown in operating position thereon;

5 Figure 2 is an end view of the parts shown in Figure 1, looking in the direction of arrows 2—2 of Figure 1 and with the parts arranged to clamp a plate of one length on the cylinder; and

Figure 3 is an enlarged portion of an end view 10 similar to Figure 2 but with the parts arranged to clamp a considerably shorter plate on the cylinder.

The improved plate cylinder 11 of this invention, as shown in the drawing, is adapted to have 15 thin metallic plates 12 stretched tightly over its periphery and secured thereto by an improved plate clamping mechanism. The clamping mechanism is of such structure that a plate 12, of a length sufficient to extend about the periphery of 20 the cylinder 11 from A to B, (see Figure 2) may be secured to the cylinder, and by the simple expedient of removing the plate clamping mechanism in a segment part 13, which is set into the cylinder 11 at its periphery, reversing the segment part 13 in the cylinder 11, and then replacing the clamping mechanism, a plate of a length sufficient 25 to extend about the cylinder from A to C may then be clamped on the cylinder.

The segment part 13 (see Figure 1) extends 30 lengthwise of the cylinder 11 from one end to the other and is secured thereto by a plurality of spaced apart screws 14 and 15, which extend through the segment part 13 and screw thread into threaded openings 16 and 17 respectively, 35 provided in the cylinder 11, when the segment part 13 is in the position shown in Figures 1 and 2. When the segment part 13 is removed from the cylinder 11 and reversed into the position shown in Figure 3, the respective screws 14 and 15 screw 40 thread into threaded openings 18 and 19 respectively, provided in the cylinder 11.

The segment part 13 is provided with a recess 45 21, which extends lengthwise thereof its entire length. The recess 21 is disposed in the part 13 considerably off-center and is of sufficient width to receive a plate clamping bar 22 carrying a plurality of clamping lugs 23, and to permit adjusting them peripherally about the cylinder 11, and is of sufficient depth to dispose them entirely 50 within the dimensions of the cylinder.

The plate clamping bar 22 extends substantially the entire length of the segment part 13 and is secured to the segment part 13 by a plurality of spaced apart screws 24, which extend 55 through elongated openings 25 in the bar 22 and

are screw threaded into threaded openings 26 in the segment part 13. The threaded openings 26 are disposed substantially midway between the side walls 27 and 28 of the recess 21. The openings 25 are elongated circumferentially of the cylinder to permit adjustment of the bar 22 peripherally about the cylinder 11 within the recess 21, the elongated openings 25 being wider than the diameter of the screws 24 to permit slight misalignment of the bar 22 in the recess 21 when this is desired.

Along the front side 29 of the bar 22, a raised plate engaging jaw 31 is formed over which an edge 32 of the plate 12 is disposed to be clamped thereagainst by jaws 33 of the clamping lugs 23, which are forced downwardly to clamp the plate edge 32 against the jaw 31, by spaced apart screws 34 and 35, the lugs 23 being fulcrumed along their rear edges 36 upon a raised rib 37 provided along the rear side edge 38 of the bar 22 for this purpose. Coiled springs 39 react against the lugs 23 to raise them out of clamping engagement with the plate edge, when the screws 34 and 35 are loosened.

Spaced apart screws 41, screw threaded into the bar 22 and extending therefrom at both sides, have their threaded ends 42 shouldered to press against a hardened metal block 43 and force it against the side wall 28 of the recess 21 (as seen in Figure 3), and thereby stretch a plate 12 held between the jaws 33 and the raised jaw 31 on the bar 22. In the construction shown, the block 43 is secured to the threaded end 42 of each screw 41 by riveting it into a counterbore 44 in the block 43.

The other edge 45 of the plate 12, (see Figure 2), is secured to the cylinder 11 by a conventional form of clamp mechanism disposed in a recess 46, provided to receive it. This clamp mechanism includes a block 47 to which the plate edge 45 is clamped by a clamp plate 48 secured by screws 49.

When it is desired to secure a shorter plate to the cylinder 11, such as one having a length that it would extend about the cylinder from A to C, the bar 22 with its associated clamp lugs 23 is removed from the segment part 13 by removing the screws 24. The segment part 13 is then removed from the cylinder 11 by removing the screws 14 and 15, and is then reversed, and the screws 14 and 15 are screwed into the openings 18 and 19 respectively. The bar 22 with its associated clamp lugs 23 is then replaced and secured in the recess 21 by means of the screws 24, with the hardened metal blocks 43 abutting the side wall 28 of the recess 21, as shown in Figure 3.

From the above description, it is obvious that provision has been made in a plate cylinder structure, whereby the cylinder may be arranged to accommodate plates of different lengths in an expeditious and efficient manner.

It will be seen that the bar 22 is reversible with respect to the segment part 13 and that the latter is reversible with respect to the cylinder, but that in changing from one length of plate to another length for which the mechanism is suitable, the segment part is the only member which is reversed with respect to the cylinder, the reversal of the segment part being effective to move the clamp bar either forward or backward with respect to the cylinder rotation and thus accommodate a plate extending to either the B or C locations.

It will be understood that the adjusting screws 75

41 provide for movement of the clamp bar 22 to the extent necessary to hold plates that vary in length to a certain extent either side of the B position or either side of the C position, and hence the use of the device is not limited to two definite lengths of plates, and obviously by increasing the width of the opening 21 and the length of the screws 41, a greater range of adjustment may be provided than with the arrangement proportioned as shown in the drawing.

It will be understood also that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In a plate cylinder for a printing machine adapted to print from relatively thin printing plates, a movable and reversible segment part having an off-center recess, set into the cylinder at its periphery, and a plate edge clamping and stretching mechanism removably secured to the segment part within the recess, and reversible with respect thereto.

2. In a plate cylinder, means to clamp plates of different lengths about and upon the periphery of the cylinder including means to clamp a first edge of either a long or a short printing plate to the cylinder, and a removable and reversible segment having means to clamp a second edge of a relatively short plate to the cylinder when the segment is secured to the cylinder in one manner and to clamp a second edge of a longer plate to the cylinder when the segment is reversed.

3. In a plate cylinder, means to clamp printing plates of different lengths about and upon the periphery of the cylinder including means to clamp one edge of a plate to the cylinder, a reversible segment part having an off-center recess, set into and removably secured to the cylinder, and a plate edge clamping device removably secured to the segment part.

4. In a plate cylinder having means to clamp plates of different lengths about and upon its periphery, means to clamp one edge of a plate to the cylinder, a reversible segment part having an off-center recess, set into the periphery of and removably secured to the cylinder and extending lengthwise thereof substantially the entire length of the cylinder, a plate clamping bar removably and adjustably secured to the segment plate, and a plate clamping jaw secured on the plate clamping bar.

5. In a plate cylinder having means to clamp plates of different lengths about and upon its periphery, means to clamp one edge of a plate to the cylinder, a reversible segment plate set into the periphery of and removably secured to the cylinder, the segment plate having an off-center seat and extending lengthwise of and substantially the entire length of the cylinder, a plate clamping member removably and adjustably secured to the seat of the segment plate, a plate clamping jaw secured on the plate clamping member, and means to adjust the plate clamping member with the plate clamping jaw thereon in respect to the segment plate to stretch

a plate extending peripherally about the cylinder between them and the plate clamping means.

6. In a plate cylinder, a segment part having an off-center recess therein set into the periphery of the cylinder and adapted to be reversed in position therein, means to secure the said part to the cylinder in either position, a plate clamping device mounted in the recess in the segment part and adapted to be reversed in position therein, and means to adjust the said device relatively to the said part and circumferentially with respect to the cylinder to tighten a plate about the cylinder.

7. In a plate cylinder for a printing machine, the said cylinder having a recess, a first plate clamp mechanism adapted to engage one edge of a printing plate, a plate clamp carrier within the said recess, having an arcuate surface corresponding to the periphery of the cylinder and an off-center slot, and a second plate clamp mechanism secured within the slot and adjustable with respect to the carrier to clamp a plate.

8. In a plate cylinder for a printing machine, a first plate clamp mechanism adapted to engage one edge of a printing plate, a reversible plate clamp carrier having an arcuate plate supporting surface and an off-center slot, and a second plate clamp mechanism secured within the slot and adjustable with respect to the carrier to clamp a plate.

9. In a printing machine, in combination, a plate cylinder adapted to have a thin plate wrapped thereabout, a plate edge clamp secured to the cylinder, the cylinder having an axially extending recess formed in its peripheral surface and circumferentially spaced from the plate edge clamp, a segment plate removably secured in the recess in the cylinder and being reversible therein, the segment plate having an off-center recess formed in its outer surface, and a second plate edge clamp removably secured in the recess in the segment plate.

10. In a printing machine, in combination, a plate cylinder adapted to have a thin plate wrapped thereabout, a plate edge clamp secured to the cylinder, the cylinder having an axially extending recess formed in its peripheral surface and circumferentially spaced from the plate edge clamp, a segment plate removably secured in the recess in the cylinder and being reversible therein circumferentially of the cylinder, the segment plate having a recess formed in its outer surface, extending circumferentially of the cylinder and terminating nearer to one edge of the segment plate than to the other edge, and a second plate edge clamp removably secured in the recess in the segment plate and being reversible therein to face either edge of the segment plate.

11. In a printing machine, in combination, a plate cylinder adapted to have a thin plate wrapped thereabout, a plate edge clamp secured to the cylinder, the cylinder having an axially extending recess formed in its peripheral surface and circumferentially spaced from the plate edge clamp to form opposing shoulders, a segment plate removably secured in the recess in the cylinder with its edges abutting the shoulders and being reversible therein to abut opposite edges with opposite shoulders, the segment plate having an off-center recess therein extending the length thereof to form opposing shoulders, and a second plate edge clamp removably se-

cured in the recess in the segment plate and including an adjusting means in engagement with one of the shoulders of the segment plate and being reversible therein to cause the adjusting means to engage the opposite shoulder.

12. In a plate cylinder for a printing machine, a first means adapted to clamp one edge of a relatively thin printing plate on the cylinder, a second means adapted to engage and clamp the opposite edge of the plate on the cylinder, the said second means being removably secured to a reversible member fastened to the cylinder and having an off-center recess arranged to receive the second means, the said second means being

15 arranged to engage and clamp the edge of a plate of one length extending peripherally about the cylinder when the member is fastened to the cylinder in one position, and the edge of the plate of a different length when the member is fastened to the cylinder in a reversed position.

16 13. In a printing machine cylinder having a peripheral surface adapted to receive a printing plate formed of sheet material, a first plate clamping means at one edge of the plate receiving surface and adapted to clamp one edge of a printing plate, a recess in the cylinder at the

25 opposite edge of the plate receiving surface, a segment member having an arcuate surface conforming to the periphery of the cylinder, a second plate clamping means adapted to be supported adjacent the arcuate surface of the segment member and arranged to engage the opposite edge of the printing plate, and means to secure the segment member and the second

30 clamping means in the recess in one operative relationship, with the clamping means between the arcuate surface of the segment member and the plate receiving surface, to clamp a relatively short plate on the cylinder, and alternatively, to secure the segment member and the second

35 clamping means in another operative relationship, with the arcuate surface of the segment member between the clamping means and the plate receiving surface, to clamp a relatively long plate on the cylinder.

40 14. In a plate cylinder for a printing machine adapted to print from plates formed of sheet material, a continuous plate receiving surface having an area at least equal to the printing area of a printing plate, a first clamping device

50 adapted to clamp one edge of the printing plate on the cylinder, a recess in the cylinder adjacent the opposite edge of the plate thereon, a segment member adapted to be secured in the recess and having an arcuate surface corresponding to the

55 periphery of the cylinder, means to secure the segment member in a first position in the recess with its arcuate surface adjacent the edge of the plate receiving surface and effectively extending the area thereof, and alternatively, to

60 secure the segment member in a second position in the recess with its arcuate surface spaced from the plate receiving surface, a second plate clamping device adapted to draw the plate tight on the cylinder, and means adapted to secure

65 the second clamping device beyond the arcuate surface of the segment member when the said arcuate surface is in the first position, to clamp a relatively long plate, and alternatively, to secure the second clamping device between the plate receiving surface and the arcuate surface when the latter is in the second position, to clamp a relatively short plate.

WILLIAM F. HUCK.
